United States Patent Office

Des. 225,729

Patented Jan. 2, 1973

225,729

BOTTLE

Ira W. Schwartz, Great Neck, N.Y., assignor to Shulton, Inc., Clifton, N.J.

Filed Sept. 21, 1970, Ser. No. 25,073

Term of patent 14 years

Int. Cl. D9—01

U.S. Cl. D9—147

Fig 2

Fig 3

FIG. 1 is a front elevational view of a bottle showing my new design;

FIG. 2 is a top plan view thereof; and

FIG. 3 is a bottom plan view thereof.

I claim:

The ornamental design for a bottle, substantially as shown.
